SYSTEM OF CONNECTIONS.

1,387,433.

Specification of Letters Patent. Patented Aug. 9, 1921.

Application filed September 3, 1920. Serial No. 408,088.

To all whom it may concern:

Be it known that I, HERMANN SUNDHAUSSEN, residing at Essen, Germany, a citizen of the German Republic, have invented a certain new and useful Improvement in Systems of Connections, (for which I have filed an application in Germany, January 2, 1917,) of which the following is a specification.

10 The subject matter of the present invention is a system of connections intended to regulate the strength of a current in the divisions of a two part divided current circuit, in which the variable parts of the system are arranged on four members movable relatively to each other thus affording a means of either keeping the strength of the current of equal value in both divisions of the divided current circuit when one of the 15 said members moves relatively to the other or varying it in unequivocal dependence upon the amount of the movement.

20 The invention will now be described with the aid of the accompanying diagrammatical drawing.

25 A denotes a cylindrical member adapted to rotate about its axis to which a conducting piece a^1 is rigidly attached. The conducting piece a^1 is electrically connected to the positive pole of a source of current and rubs over a circularly shaped variable resistance b^1 which is rigidly connected to a member B adapted to rotate about the axis of rotation of the member A. The two ends 30 of the variable resistance b^1 are each electrically connected by conductors b^2 and b^3 with the ends c^3 and c^4 of two similarly shaped variable resistances c^1 and c^2 , both of which are rigidly attached to a member C adapted to rotate about the common 35 axis of rotation of the members A and B. Over the resistances c^1 and c^2 and in rubbing contact therewith two conducting pieces d^1 and d^2 , are mounted on a member D adapted to rotate relatively to the member C and are connected by the conductors d^3 and d^4 by means of a common conductor d^5 to the negative pole of the source of current.

40 All the variable resistances extend in the 50 manner shown in the drawing over the same central point angle and are so constructed that equal central point angles correspond to equal variations of the resistance.

45 As can be seen from the drawing, the conducting piece a^1 forms the starting point of

a two-part divided current, one current division of which is formed by one part of the variable resistance b^1 , the conductor b^2 , the part of the variable resistance c^1 connected to the conducting piece d^1 and the conductor d^3 , and the other current division of which is formed by the other part of the variable resistance b^1 , the conductor b^3 , the part of the variable resistance c^2 connected to the conducting piece d^2 and the conductor d^4 .

50 When the above described system of connections is traversed by a current and all the parts are in the position shown in the drawing, it is obvious that the strength of the current on both current divisions possesses an equal value.

55 Now if the member A for example and consequently the conducting piece a^1 rigidly connected thereto be rotated in the direction of the arrow α through an angle α that part 60 of the variable resistance b^1 , which lies in the current division containing the resistance c^1 , will be reduced by an amount corresponding to the angle α , while that part of the variable resistance b^1 , which lies in the current division which contains the variable resistance c^2 , will be increased by a like amount 65 also corresponding to the angle α .

70 The total resistance of the first mentioned current division will in this way be diminished by the same amount that the total resistance of the last mentioned current division increases, no change having taken place in the relative position of the other parts affected. Accordingly, the current strength 75 in each of the two divisions is positively determined by the angle of rotation α .

75 The same result takes place, as can be readily seen without further description, if in place of the stationary member A, the member B, the member C or the member D 80 be rotated through an angle α .

85 If on the other hand the members B and C for example be rotated conjointly in the direction of the arrow α through the angle α , then with the construction of the variable resistances shown in the drawing that part 90 of the variable resistance b^1 situated in the current division containing the variable resistance c^1 , will be increased by an amount 95 corresponding to the angle of rotation α , and the part of the variable resistance c^1 situated in the same current division will be decreased by a like amount. Furthermore 100 on the aforesaid conjoint rotation of the 105

members B and C that part of the variable resistance b^1 lying in the other current division will be reduced by the same amount (corresponding to the angle α) that the part 5 of the variable resistance c^2 lying in the last mentioned circuit is increased. The total value of the resistance lying in each current division will therefore not be altered by the aforesaid conjoint rotation of the members 10 B and C, and the strength of the current in each current division retains its value unchanged.

Corresponding conditions occur if the members B and C remain at rest and the 15 members A and B are rotated in the direction of the arrow x through an angle α . In this case also the total value of the resistance lying in the two current divisions does not alter on the aforesaid rotation of the 20 members A and D, and the strength of the current consequently retains its original value during the rotation.

In like manner, as can be seen without further explanation, no change takes place 25 in the strength of the current flowing in the two current divisions, when the two members C and D are rotated conjointly.

Finally the value of the strength of the current in the two current divisions remains 30 unaltered if the members A and C and B and D be rotated conjointly, but in this case however the conductors b^2 and b^3 would be connected to the two other ends of the variable resistances c^1 and c^2 .

35 The above described system of connections affords a means of varying the strength of the current in the two divisions of a two-part current system, in which the acting parts are mounted on four members 40 adapted to be moved relatively to each other, such variations being proportional to the angle of rotation when one of the members concerned is rotated and of keeping it unaltered on the rotation of two of the members 45 concerned simultaneously and in the same direction.

The provision of these two possibilities is

of particular value when it is required to use this system in connection with a long distance controlling device in which a conjoint rotation of the two members cannot be avoided and where the said rotation is not to have any influence on the adjustment of the part to be adjusted. 50

Without altering the essential feature of the invention it would be quite possible to make the variable resistances rectilinear for example. In this case the members corresponding to the members A, B, C and D would have to be longitudinally movable 60 relatively to each other.

Claims.

1. System of connections for regulating the strength of a current in the divisions of a two-part divided current circuit, characterized by the fact, that two points of a variable resistance (b^1) movable relatively to a conducting piece (a^1) electrically connected to one pole of a source of current which forms the starting point of the current division, are respectively connected to one end of two variable resistances (c^1 , c^2) movable conjointly relatively to the aforesaid variable resistance (b^1) and that the conjointly movable variable resistances (c^1 , c^2) 75 have in rubbing contact therewith respectively two conducting pieces (d^1 , d^2) also movable conjointly relatively thereto and from which a common conductor (d^3) leads to the other pole of the source of 80 current.

2. System of connections according to claim 1, characterized by the fact that all the variable resistances (b^1 , c^1 , c^2) are of circular shape, are adapted to rotate about 85 the same axis and are so constructed that equal central point angles correspond to equal variations of the resistances.

The foregoing specification signed at Es- 90 sen, Germany, this 20th day of May, 1920.

HERMANN SUNDHAUSSEN.
